United States Patent Office

Des. 184,032
Patented Dec. 2, 1958

184,032

FIGURINE

James A. Unwin, Saugatuck, Mich., assignor to Hopkins
Syndicate Inc., Chicago, Ill., a corporation of Illinois

Application November 15, 1957, Serial No. 48,495

Term of patent 14 years

(Cl. D29—23)

FIG. 1

I claim:

The ornamental design for a figurine, substantially as shown.
